Primary Examiner — George D Kirschbaum*Assistant Examiner* — Jennifer Watkins(74) *Attorney, Agent, or Firm* — Thomas A. Dougherty;
Lewis Brisbois Bisgaard & Smith LLP(57) **CLAIM**

The ornamental design for a surgical drape, as shown and described.

DESCRIPTION

FIG. 1 is a perspective view of the surgical drape design.

FIG. 2 is a front view of the surgical drape design.

FIG. 3 is a back view of the surgical drape design.

FIG. 4 is a top and bottom view of the surgical drape design.

FIG. 5 is a right and left side of the surgical drape design.

FIG. 6 is a detail view of the surgical drape design from FIG. 1; and,

FIG. 7 is a cross-section detail of the surgical drape design from FIG. 6.

The evenly dashed broken lines illustrating a rectangular opening in the surgical drape are for the purpose of illustrating portions of the surgical drape and form no part of the claim. The unevenly dashed broken lines are for the purpose of illustrating the cut lines of the sectional views and form no part of the claim. The dotted lines shown in FIGS. 1 and 2, extending from the edges to the center of the surgical drape, illustrate claimed subject matter.
